UNITED STATES PATENT OFFICE

2,563,238

ELECTRODE UNIT

Rea I. Hahn, Rochester, N. Y., assignor to General
Motors Corporation, Detroit, Mich., a corpora-
tion of Delaware

Application July 28, 1949, Serial No. 107,153

4 Claims. (Cl. 219—6)

1

This invention relates to the manufacture of tubing and its object is to provide an electrode unit suitable for use in heating tubing by passage of electric current through it while travelling in a non-oxidizing atmosphere, said unit providing a chamber in which a tubing contacting electrode is located and which receives an inert or partially reducing gas, and providing for facile location of the tubing in the chamber and in contact with the electrode by lateral movement of the tubing as well as by threading the tubing longitudinally.

In the disclosed embodiment of the invention this object is accomplished by providing chamber wall portions, one being fixed and the other movable from a closed position to an open position to expose a channel provided by the fixed portion into which the tubing can be placed by lateral movement thereof.

Further objects and advantages of the present invention will be apparent from the following description, reference being had to the accompanying drawings, wherein a preferred embodiment of the present invention is clearly shown.

In the drawings:

Fig. 1 is a side view of the electrode unit.

Fig. 2 is a sectional view on line 2—2 of Fig. 1.

Fig. 3 is a view in the direction of arrow 3 of Fig. 2.

Fig. 4 is a view in the direction of arrow 4 of Fig. 2.

Fig. 5 is a sectional view on line 5—5 of Fig. 1.

Fig. 6 is a sectional view on line 6—6 of Fig. 5.

Fig. 7 is a sectional view on line 7—7 of Fig. 1.

The supporting frame-work of the device comprises end plates 10, side plates 11 and a bottom plate 12 of non-conducting refractory material, such as "transite," which are attached together in box-like formation. There is also a metal bottom plate 13 attached to plates 10 (Fig. 2). This frame is slideable on horizontal supports provided for example by parallel angle bars 14 to enable the unit to be located in the desired position relative to other electrode units, said units being for example parts of a tubing annealer providing for heating the tubing by passing electric current through the portion of the tubing between the units. The frame is secured in the desired position on the angles 14 by a clamp 15 of "transite" secured by a screw 16 threaded into plate 13.

The plates 10 support bearings 20 for a shaft 21 preferably of copper and carrying a copper disc 22 partially submerged in mercury 23 contained in a copper vat 24 attached to the adjacent plate 10. The vat 24 is to be connected with

2

a current source terminal. Vat 24 supports a bar 25 to which is attached a block 26 providing for connection with a source of cool water conducted by a pipe 27 extending through a bore in the shaft 21 and terminating near the left end of the shaft. This water flows from the right end of the shaft upon a lip 28a of the vat 24 and is received by a suitable drain not shown.

Shaft 21 supports a grooved, copper electrode roll 28 secured by a nut 29 and cooperating with a grooved, copper contactor roll 30 secured by a nut 31 to a shaft 32 journaled in bearings 33 supported by "transite" plates 34 attached to metal plates 35 pivoted on screws 36 supported by plates 11 (Fig. 1). Plates 35 and parts supported thereby gravitate in a counterclockwise direction so that contactor roll 30 is urged by forced gravity upon the tubing which is received between it and the roll 28. A plate 40 provides a hole 21a for receiving shaft 21 and a hole 32a for receiving shaft 32, the latter hole being of such size as to permit upward movement of the roll 30 sufficiently to place the tubing between it and the roll 28 by lateral movement of the tubing.

The unit provides a chamber for retaining inert or reducing gas at the electrode 28 and contactor 30 and beyond them. This chamber is enclosed by a housing comprising fixed and movable members. The fixed member includes a metal frame member 41 (Fig. 7) attached to plate 40 and supporting a "transite" side wall liner 42 to which are attached as shown in Fig. 6 bottom liners 43 and 44 and top liners 45 and 46 also made of "transite." Between the top and bottom liners, there is a tubing receiving channel. Brackets 47 having shanks 47a press fitted into aligned holes provided by plates 40, 10 and 13 (Fig. 2) support screws 48 providing pivots for bars 49 which are welded to a metal frame member 50 supporting a "transite" side wall liner 51 (Fig. 7) adapted to engage the lining members 43—46 to provide an enclosure for the tubing. Parts 50 and 51 provide the movable member of the housing. The plate 40 supports brackets 52 carrying pins 53 providing pivots for latch levers 54 for hooking over a latch bar 55 connecting the levers 49. Levers 54 are connected by a handle bar 54a.

Inert or partially reducing gas is conducted by pipe 60 (Fig. 6) into the chamber enclosed by housing members 41 and 50. The pressure of the gas is sufficient to cause it to prevent entrance of air into the chamber. This gas flows into refractory tubes (not shown) which are connected in any suitable manner with the refractory liner

members of the chamber. To limit the escape of gas around the rolls 28 and 30, the lining members 43-46 are shaped to terminate close to these rolls and the liner 42 is recessed or counterbored at 28a to provide slight clearance with the roll 28 and counterbore 30a to provide slight clearance with the roll 30.

By lifting the handle 54a, the latch levers 54 are lifted in order to release the movable housing member 50 so that it can be swung counter-clockwise (Fig. 2) about the pivot screws 48, thereby exposing the tubing-receiving channels between the liners 43-45 and the liners 44-46 (Fig. 6). By lifting the roll 30, the tubing can be placed in these channels without requiring the tubing to be threaded longitudinally. It is likewise an advantage to be able to remove the tubing from the channels by lateral movement thereof. For example, if the tubing should buckle and jam in the unit due to accidental overheating, the buckled portion of the tubing can be moved laterally from the channels and be cut out without first requiring longitudinal movement of the tubing to locate the buckled portions beyond one end or the other of the unit or other units connected therewith.

While the embodiment of the present invention as herein disclosed, constitutes a preferred form, it is to be understood that other forms might be adopted.

What is claimed is as follows:

1. An electrode unit comprising an electrode for contacting moving tubing, a tubing contactor for urging the tubing against the electrode, means supporting the contactor for movement against the tubing or away from the tubing to permit placing the tubing between the electrode and contactor, a housing receiving portions of the electrode and contactor and providing a gas receiving chamber at the electrode and contactor and extending therefrom, said housing including a fixed member providing a channel in which the tubing can be placed by lateral movement thereof as well as by threading it when the contactor is separated from the electrode and including a member movable from a position exposing the channel for placing the tubing therein into a position closing the channel and means for retaining the movable member in channel closing position.

2. An electrode according to claim 1, in which the gas chamber housing members each have a channel shaped metal frame, in which the fixed frame member supports side wall liner and bottom and top wall liners of refractory material between which the tubing-receiving channel is provided, in which the movable frame member supports the other side wall liner of refractory material, and in which means are provided for supporting the movable frame member for movement from a

position exposing the channel for placing the tubing therein into a position wherein the side wall member carried thereby contacts the bottom and top wall liners supported by the fixed metal frame.

3. Apparatus for heating metal tubing electrically while said tubing is being moved longitudinally, comprising an electrode for contacting the moving tubing, a member for urging the tubing against the electrode, movable means supporting said member and so constructed that it may be operated to move said member far enough from the electrode to permit the tube to be placed between the electrode and said member by a lateral movement of said tube, a housing into which said member and said electrode project and having a channel formed therein through which the tube passes, means for introducing a gas into said chamber, said chamber having a pivoted wall movable to a position to permit access thereto so that the tube can be inserted in said channel by a lateral movement thereof and movable also to a position to close said channel and means for holding the wall in its channel closing position.

10 4. Apparatus for heating metal tubing electrically while said tubing is being moved longitudinally, comprising an electrode for contacting the moving tubing, a member for urging the tubing against the electrode, movable means supporting said member and so constructed that it may be operated to move said member far enough from the electrode to permit the tube to be placed between the electrode and said member by a lateral movement of said tube, a housing into which said member and said electrode project and having a fixed portion forming a channel through which the tube passes and a pivoted wall movable to permit access to said channel so that the tube may be positioned in said channel by a lateral movement of the tube and to a position to close said channel, means for introducing a gas into said chamber, said fixed and movable parts of said chamber having liners of refractory material so that when the movable wall is in closed position, the tube which passes therethrough is surrounded by walls of refractory material, and means for holding the movable wall in its channel closing position.
